UNITED STATES PATENT OFFICE.

JACOB TIM, OF NEW YORK, N. Y.

ADJUSTABLE CAP.

1,262,409.

Specification of Letters Patent. Patented Apr. 9, 1918.

Application filed October 29, 1917. Serial No. 199,099.

To all whom it may concern:

Be it known that I, JACOB TIM, a citizen of Russia, and a resident of the city of New York, borough of Manhattan, in the 5 county and State of New York, have invented a new and Improved Adjustable Cap, of which the following is a full, clear, and exact description.

This invention relates to wearing apparel and deals particularly with a cap.

The invention has for its general objects to provide a cap which is adjustable as to size, so that it can be worn by different persons with equal comfort and fit in the proper 15 manner, whereby the retailers need keep only one size hat in stock, and also whereby the user can easily and quickly adjust the size to fit his own head.

A more specific object of the invention is 20 the provision of a cap which is provided with a plurality of plackets in the rear part with suitable adjusting means at the plackets whereby the head band portion of the cap can be made of any desired size.

With such objects in view and others 25 which will appear as the description proceeds, the invention comprises various novel features of construction and arrangement of parts which will be set forth with particularity in the following description and claim appended hereto.

In the accompanying drawing, which 30 illustrates one embodiment of the invention and wherein similar characters of reference indicate corresponding parts in all the views,

Figure 1 is a rear perspective view of the cap shown on the head of the wearer;

Fig. 2 is a rear view in perspective; and 40 Figs. 3 and 4 are bottom plan views showing the cap adjusted to different sizes.

Referring to the drawing, A designates the cap, which is made after any approved design, and at the rear are a plurality of 45 plackets 1, and at each placket are a plurality of buttoning or closing devices, such as the studs 2, and complementary sockets 3. The cap is made of sector-like sections and the edges are sewed together only part 50 of the way where the plackets are located, and the plackets are formed by leaving the

edges of adjacent sectors unsewed. In the present instance three plackets are shown and two sets of studs and sockets at each placket, whereby it is possible to close the 55 plackets so that the cap can be adjusted to six different sizes. In Fig. 3 the cap is shown adjusted to its largest size, and in Fig. 4 adjusted to its smallest size, and by properly selecting the coöperating studs 60 and sockets the other four intermediate sizes can be obtained.

The cap with the improvement embodied therein is of attractive and neat appearance, and by reason of the adjustment in the size 65 65 the storekeeper need require only one stock of caps for different sizes of heads, and the owner can adjust the cap to fit his own head or the head of the person to whom he wishes to lend it, which is a desirable feature 70 for automobilists, sportsmen or the like, when they wish to furnish caps for their guests.

From the foregoing description taken in connection with the accompanying drawing, the advantages of the construction and method of operation will be readily understood by those skilled in the art to which the invention appertains, and while I have described the principle of operation, together with the article which I now consider to be the best embodiment thereof, I desire to have it understood that the article shown is merely illustrative and that such changes may be made when desired as fall within the 85 scope of the appended claim.

Having thus described my invention, I claim as new and desire to secure by Letters Patent:

A cap having a soft crown composed of 90 sector-like sections sewed together with seams radiating from a common point, certain of the seams extending short of the bottom edge of the cap, whereby plackets are formed, and a plurality of complementary fasteners spaced apart on opposite sides of each placket to permit the size of the cap to be adjusted, the fasteners on one side of the placket being on the inside of the cap and the others on the opposite side 95 100 of the placket being on the outside.

JACOB TIM.
